UNITED STATES PATENT OFFICE.

GEORGE W. CROSS, OF PITTSTON, PENNSYLVANIA.

DESIGN FOR A SCREEN.

SPECIFICATION forming part of **Design No. 27,114, dated May 25, 1897.**

Application filed August 17, 1896. Serial No. 603,086. Term of patent 14 years.

To all whom it may concern:

Be it known that I, GEORGE W. CROSS, a citizen of the United States, residing at Pittston, in the county of Luzerne and State of Pennsylvania, have invented and produced a certain new and original Design for Screens, of which the following is a specification, reference being had to the accompanying drawing, forming a part thereof.

The invention concerns a certain novel design or configuration for a screen adapted for the separation of coal, ore, stone, &c. Such design is illustrated in the accompanying drawing, which is a perspective view of a screen-segment the body of which is so fashioned as to embody said design or configuration.

Referring to the drawing it will be seen that the plate is provided with a number of rectangular interstices B, the corners of which are slightly rounded. These interstices are arranged in line in one direction, as well as in the direction at a right angle thereto. Each interstice is bounded by four webs, two of which are depressed or curved downwardly

and the other two of which are elevated or curved upwardly. Thus, considering one interstice B and the webs surrounding it, the web b is elevated or curved upwardly while the web directly opposite is depressed or curved downwardly. The web b' is depressed or curved downwardly, while the web directly opposite is elevated or curved upwardly. The remainder of the screen-body consists of repeats of the configuration described, and the effect of this is to make the web-bars continuous and undulatory in form, each web having a convexity where it bounds one interstice and a concavity where it bounds the next adjacent interstice.

Having now described the invention, what I claim is—

The design for a screen herein shown and described.

This specification signed and witnessed this 45
31st day of July, 1896.

GEORGE W. CROSS.
